Patented Dec. 9, 1919.

FIG. 1.

FIG. 2.

WITNESS:

Ed. Stark.

INVENTOR:

JOHN A. EMERSON.

BY

Michael J. Stark & Son,
ATTORNEYS.

UNITED STATES PATENT OFFICE.

JOHN A. EMERSON, OF CHICAGO, ILLINOIS.

DEVICE FOR REMOVING CLINKERS FROM FURNACES.

1,324,498.

Specification of Letters Patent.

Patented Dec. 9, 1919.

Application filed August 30, 1919. Serial No. 320,805.

To all whom it may concern:

Be it known that I, JOHN A. EMERSON, a citizen of the United States, and resident of the city of Chicago, in the county of Cook and State of Illinois, have invented certain new and useful Improvements in Devices for Removing Clinkers from Furnaces; and I do hereby declare that the following description of my invention, taken in connection with the accompanying sheet of drawings, forms a full, clear, and exact specification, which will enable others skilled in the art to which the said invention appertains to make and use the same.

15 This invention has general reference to clamping devices; and it consists, essentially, in the novel and peculiar combination of parts, and details of construction, as hereinafter first fully set forth and described, and then pointed out in the claim.

20 The object of this invention is the production of an efficient, serviceable, convenient, and comparatively inexpensive device for removing clinkers from furnaces and the like.

25 It is a well-recognized fact that there is considerable difficulty experienced in removing clinkers from furnaces in operation, partly due to the heat emitted when the fire doors are open, and the difficulty in catching the clinkers for removal, especially in furnaces where the grate bars are below the fire door, and cannot be easily reached by the means in common use.

30 35 To overcome these difficulties, I provide a device which can be readily handled and which combines a poker or slice bar with means for grasping clinkers and hold them so that they may be effectively removed from the furnace while the fire is burning.

40 In the drawings, which illustrate the preferred embodiment of my invention, and form a part of this specification,—

Figure 1 is an elevation of my improved slice bar and fire tongs combined. Fig. 2 is a similar view of the device as it appears after having been rotated through an angle of 90 degrees from that shown in Fig. 1.

45 Like parts are indicated by the same characters and symbols of reference in both figures.

50 A, in the drawings designates an iron rod of proper length and diameter, which rod is, preferably, tubular in form and which 55 may be, for general purposes, a commercial iron pipe of $\frac{3}{4}$ inch diameter, which meas-

ures externally approximately 1 inch in diameter, but may be larger in diameter when found necessary or desirable. This bar is, preferably, flattened at one of its 60 ends, as at 12, and terminates in a blunt point 13 or a separate flat bar may be welded into the lower end of this tube, if desired.

To this flattened portion 12 there is pivotally connected, by a pivot 14, a lever B, 65 which lever is likewise a flat bar bent to approximate V-shape, and terminating in an inwardly turned hook 16, the terminal edge of which is somewhat sharpened.

Near the upper terminal of the rod A 70 there is provided a pivot 17, to which is connected a hand lever 18, of approximately V-shape, by its arm 19, which is forked at this point, and flattened as at 20. To this flattened member there is hitched a rod 21, 75 which extends downwardly and has its lower end connected to the arm 22 of the lever B, in a hole 25 therein.

In the tubular rod A there are spaced apart openings 23, 24, the pull-rod 21 entering the tube through the opening 23, and passing out of the same at 24, so that this rod, which may be a comparatively light wire, (it being subjected to tension only) will not be disturbed when the device is being used.

80 At a point 26, opposite the opening 25 in the arm 22, there is attached a wire rod 27, and from the tube A extends a loop or eye 28, to which loop there is attached at one 90 of its ends a coil spring 29, the other end of said spring being hitched to the upper end of the wire rod 27. This spring 29 is under slight tension to keep the free end of the lever B away from the spike 12; but 95 when the hand lever 18 is properly manipulated, the rod 21 connected thereto, will cause the end of the lever B to move toward the spike 12 and grasp and hold any article that may become engaged by these elements. 100

It will now be noted that this instrument is especially well adapted for use in connection with furnaces, particularly when in operation, inasmuch as the spike 12 may perform the function of a slice bar to lift 105 the clinkers, slag, etc., from the grate and grasp them between the point 13 and 16 of the device, and then lift them out of the furnace.

The simplicity of this device is at once 110 apparent; and since it can be manufactured and sold at a very reasonable price, it will

fill a long-desired want for an instrument of the nature described.

Having thus fully described this invention, I claim as new, and desire to secure to myself by Letters Patent of the United States—

An instrument for removing clinkers from furnaces and the like, consisting, in combination, of a tubular rod, said rod having at 10 one of its extremities a flattened bar, said bar terminating in a blunt point, a curved lever pivotally connected to said flattened bar, said curved lever having one of its terminals inwardly turned, approximately at 15 right angles, the right angled portion being formed to a blunt edge, a hand lever pivotally connected to the other end of said tubular rod, a wire rod connected with one

of its ends to said curved lever at the other end of its terminals, the other end of said 20 wire rod being connected to said hand lever, there being in one side of said tubular rod an opening through which said wire rod passes into, and at the other side an opening 25 through which said wire rod passes out of said tubular rod, and means for keeping the inwardly turned end of said curved lever normally at a distance from the pointed end of said flattened bar, said means being connected to said curved lever at a point opposite that where the wire rod is connected thereto.

In testimony that I claim the foregoing as my invention, I have hereunto set my hand.

JOHN A. EMERSON.
